UNITED STATES PATENT OFFICE.

WILLIAM P. DUN LANY, OF CHICAGO, ILLINOIS, ASSIGNOR TO SEARS, ROEBUCK AND COMPANY, OF CHICAGO, ILLINOIS, A CORPORATION OF NEW YORK.

DESIGN FOR ORNAMENTAL FLEXIBLE ROOFING.

48,172.

Specification for Design.

Patented Nov. 23, 1915.

Application filed September 25, 1915. Serial No. 52,740. Term of patent 14 years.

To all whom it may concern:

Be it known that I, WILLIAM P. DUN LANY, a citizen of the United States, residing at Chicago, in the county of Cook and State of Illinois, have invented a new, original, and ornamental Design for Ornamental Flexible Roofing, of which the following is a specification, reference being had to the accompanying drawing, forming a part thereof.

The drawing is a fragmental face view of a strip of ornamental flexible roofing showing my new design.

I claim:

The ornamental design for ornamental flexible roofing, as shown.

WILLIAM P. DUN LANY.
